TUBULAR RUDDER

Robert W. Erlbacher, Cape Girardeau, Mo.

Application February 21, 1955, Serial No. 489,586

4 Claims. (Cl. 114—166)

This invention relates to a tubular rudder for marine use, and in particular is concerned with a tubular rudder which is pivoted aft of the propeller.

In the past, blade rudders have been conventionally used behind a propeller on marine vessels for steering. These rudders have been objected to in varying degree because of vibration, excessive power required in steering, poor efficiency in steering which is reflected in poor maneuverability and extremely turbulent wash. The first three of these features are reflected in disadvantages in ship operation which necessitates rugged construction and control devices. The last feature, the turbulent wash, is dangerous to surrounding small craft which are often capsized when a vessel of substantial proportions is in the neighborhood.

Attempts have been made in the past to obviate the difficulties found in the blade rudder, and one such attempt to this problem resulted in the Kort rudder. The Kort rudder consisted of a tubular shell positioned around a propeller wheel with a very small clearance for the wheel; just sufficient for the wheel to fit within the rudder. Although the turbulent wash was reduced by the Kort rudder, it has still left certain desirable features to be obtained relative to vibration, easier steering, which is reflected in less torque on the rudder stem, and greater maneuverability.

By means of this invention there has been provided a tubular rudder which is pivoted aft and spaced from the propeller wheel. This rudder receives the full force and extent of the water propelled through the propeller wheel inside the shell of the rudder and passes it outwardly through a rear opening in such a manner as to fully enclose and control the propelled wash. The rudder is of slightly smaller internal diameter than the propeller wheel to accommodate the reduced diameter of the jet stream of water propelled from the propeller which undergoes a slight contraction after leaving the propeller. Thus, a full control and enclosure of this propelled water is obtained.

Preferably, the rudder is also of an airfoil design in its wall section with the internal diameter flaring somewhat at the front behind the propeller wheel. Also, the leading front edges of the rudder are recessed at the sides between the top and bottom to provide for greater cross section of entry when the rudder is pivoted away from the straight position either to port or starboard whereby greater steering control is obtainable.

It has been found that by the use of this invention the vibration and steering power requirements have been decreased, and maneuverability or response to rudder position has been improved. The actual thrust from the propeller obtained by the use of the tubular rudder of this invention, also has been increased over the previously known blade rudders, and the Kort rudder. Further, maintenance of the propeller shaft is facilitated by use of the tubular rudder since the rudder need not be dismantled for removal of the shaft. Likewise, the wake or wash behind the tubular rudder of this invention has

2

been reduced to a smooth, even roll so as to facilitate marine traffic in the neighborhood of the ship equipped with this invention whereby marine hazards have been greatly minimized.

Accordingly, it is a principal object of this invention to provide a tubular rudder situated aft of the vessel's propeller wheel to obtain increased operating benefits.

Another object of this invention is to provide a tubular rudder aft of a propeller wheel in which the rudder has an airfoil wall design.

10 A further object of this invention is to provide a tubular rudder which has recessed side portions on its front end so that it can be pivoted behind a propeller and receive a maximum flow of race therefrom for increased maneuverability and steering efficiency.

15 Still another object of this invention is to provide a tubular rudder aft of a propeller wheel which is of a reduced size with respect to said wheel for a full control of the wheel race for the presentation of a restricted opening to accommodate the propeller race.

20 Still a further object of this invention is to provide a reduced draft tubular rudder spaced aft of a propeller which reduces vibration.

25 Still another object of this invention is to provide a tubular rudder spaced aft of the propeller which increases forward thrust of the vessel and reduces engine load.

Still another object of this invention is to provide a tubular rudder spaced aft of a propeller which increases maneuverability of the vessel and reduces power required for maintaining the rudder in a desired position.

30 Still another object of this invention is to provide a tubular rudder spaced aft of a propeller which does not increase the draft of the vessel and can be used with standard steering and propeller rigs.

35 Still a further object of this invention is to provide a tubular rudder which provides a minimum of flow restriction of water presented to the propeller when the engines are reversed so that high efficiency can be obtained in backing.

40 It is still a further object of this invention to provide a tubular rudder spaced aft of a propeller to produce a smooth wash, and thereby lessen the hazard presented to small boats in the neighborhood.

45 It is still another object of this invention to provide a tubular rudder which is adapted for use with conventional vessels and can be easily installed and maintained, and yet is of rugged construction to provide durability.

50 Yet another object of this invention is to provide a characterized tubular rudder which is symmetrical to the propeller race for high efficiency in the control of the propeller race.

55 Still a further object of this invention is to provide a backing tubular rudder which can be used forward of the propeller for steering a vessel when the engines are reversed.

Further objects of this invention will appear in the detailed description which follows and will be further apparent to those skilled in the art. Reference will now be had to the accompanying drawings showing preferred embodiments of this invention. It is to be understood, however, that these drawings are for the purpose of illustration only, and that the invention is not limited thereto.

In the drawings:

60 Figure 1 is a view in side elevation of a propeller equipped vessel provided with the tubular rudder of this invention which is partially broken away to show the side wall construction;

65 Figure 2 is a somewhat enlarged view showing the propeller and rudder combination with the flow streams of the propeller race, indicated in dotted lines;

70 Figure 3 is a view similar to Figure 2, but showing the

rudder in the hard port position with the changed flow lines of the race;

Figure 4 is a view in front elevation of the propeller looking back through the rudder of Figure 2;

Figure 5 is a force diagram showing the effect of depth below the water surface on the propeller race;

Figure 6 is a view similar to Figure 4 showing a modified form of rudder;

Figure 7 is a view partially broken away in side elevation of the modified rudder of Figure 6; and

Figure 8 is a view similar to Figure 1 showing the employment of a backing rudder positioned forwardly of the propeller.

In Figure 1, a vessel 10 is shown equipped with a conventional multibladed propeller 11 affixed to a propeller shaft 12 which is journaled within a bearing support 13. The tubular rudder is generally indicated at 14 and is spaced aft of the propeller. A rudder post or stem 15 is fixed to the rudder and extends vertically within the vessel where its pivotal operation is controlled in a known manner.

The propeller 11 is preferably equipped with a fairwater 18 which tends to equalize out the flow lines in the race of wash aft of the propeller in order to reduce turbulence. The force lines of the race are shown at 16 in Figure 2 where it can be seen that the fluid flowing through the propeller wheel and which is worked upon by the blades of the wheel is propelled aft of the wheel in the form of a generally cylindrical jet of extremely high velocity. Actually the cross-sectional shape is not exactly cylindrical as will be made more apparent hereinbelow. This generally cylindrical wheel race undergoes a partial contraction aft of the wheel or a necking-down to a point just behind fairwater where it evens out to a subsequently constant cross section until quite some distance behind the propeller (not shown) the force is dissipated. The diagrammatic showing of the force lines in the propeller race of Figure 2 represents the standard condition of a heavily loaded propeller wheel race independent of the use of any rudder at all.

This substantially cylindrical wheel race is enclosed by the tubular rudder 14 to attain full effects in thrust, maneuverability, and steering power requirements, while at the same time vibration is minimized through the rudder post 15 to the vessel. To effectuate the enclosing of the race, the rudder is made of the approximate internal diameter of the neck-down race after the race is contracted at point 17.

To determine this diameter the following procedure is followed. The cross-sectional area of each blade is obtained at its thickest part. This area is multiplied by the number of the blades and then added to the cross-sectional area of the propeller hub at the thickest part of the blades. This sum is then subtracted from the total propeller area. Lastly, for heavily loaded screws an additional 15% is subtracted as the slippage is fairly high while with more lightly loaded screws this percentage can be decreased. This diameter is generally about 80 to 90% of the diameter of the propeller wheel and varies somewhat depending upon the propeller design and the load placed upon it, as is understood in the art.

As is apparent from Figures 2 and 4, the tubular rudder 14 has an open front end 20 and rear end 21. The rudder is supported behind the propeller by the rudder stem 15 which is fixed to the rudder 14. The pivot point is spaced behind the propeller a distance approximately equal to the diameter of the propeller at a point approximately where the necking-down of the propeller race is completed. It will be noted that the top portion 23 and bottom portion 24 of the front end 20 extend forwardly of the pivot or rudder post 15, while the port side portion 25 and starboard portion 26 are both recessed with respect to the top and bottom portions. Thus, both side portions 25 and 26, as shown in Figure 2, are cut back about to the rudder stem. This provides for greater ac-

cess of entrance when the rudder is turned to the hard port position, as shown in Figure 3 where the force lines of the propeller race are given greater access of entry due to the recessed portion 25. Obviously this also applies to the starboard positioning of the rudder through recessed portion 26.

A modification of this design is shown for the rudder 14' in Figure 8 where the front bottom wall is cut back in relation to the top to provide a lower front end portion 29, which is more or less straight-edged about the lower half of the rudder. This design is suitable in debris infested waters and obviates the possibility of any debris lodging in the recesses at the side portions. Actually, this lower front end may be vertical or slant toward the rear at the bottom.

The actual wall configuration of the tubular rudder includes, besides the aforementioned straight-sided exterior surface 22, an interior surface which is of a generally airfoil configuration. Thus, the forward or leading side of the interior surface is outwardly flaring and curved at 27, after which toward the rear the curvature straightens out into a straight side 28, which provides a constant diameter bore to the rear end 21. The extent of the curvature of the surface 27 is fairly substantial along the axis 25 of the rudder so as to provide a goodly amount of surface more nearly perpendicular to the propeller race than wall 28 when the rudder is turned in a hard-over position such as shown in Figure 3.

Although the propeller race has been described as being substantially cylindrical in the description above, in actuality it may be considered to be somewhat flattened out at the bottom. Thus, due to pressure differentials which increase with the distance below the surface, namely, about 0.44 p. s. i. for each foot of depth in fresh water, there is a greater exterior pressure on the propeller race at the bottom which causes a partial flattening out, as shown in Figure 5. The force lines which are greater at the bottom, as shown in Figure 5, cause the distortion of the propeller race to be shaped as shown. In order to enclose and mate as fully as possible with this configuration of the propeller race, a tubular rudder having an internal cross section of the same general configuration as that shown in Figure 5 is shown in Figures 6 and 7. The modified rudder is indicated at 30 and is alike in all respects to the generally cylindrical shaped rudder 14 except for its cross section at the front end, and like numbers have been given for like elements.

In the modified tubular rudder 30, full acceptance and enclosure of the propeller race is effected with a maximum attainment of operating efficiency. Thus, there is no obstruction and consequently no deleterious turbulence presented in the tubular rubber to the flow of the propeller race passing through it. Although this form of the rudder is somewhat more difficult to construct, its operating advantages are improved over the rudder 14.

In this rudder the front end 31 is of the partially flattened configuration shown conforming with the wheel race in Figure 5. This configuration is then changed within the rudder to the circular open end 21 as this shape is most efficient for the race exhaust in the benefits to be derived from this invention.

The dimensioning of the rudder 14 and rudder 30 is substantially the same with respect to relative spacing behind the propeller blade. Thus, for rudder 14, as has been previously mentioned, the internal diameter of the circular rudder wall 28 at the rear end is approximately 80 to 90% of the diameter of the propeller 11. In the rudder 30, the cross-sectional area at the front end is the same as that for the rudder 14. However, since the configuration is changed somewhat, the major axis at the front end is greater than the internal diameter of wall 28 and may be increased up to approximately the diameter of the propeller while the minor axis is less and may be about 75 to 85% of the propeller diameter. The most desirable length of the rudder from the front, i. e., be-

tween top and bottom portions 24 and 23 and the end 21, is approximately equal to the diameter of the propeller. It will, however, be understood that this invention is not limited to these figures since, as has been previously mentioned, propeller design and operational requirements may provide different dimensions, as will be understood in the art.

With respect to the spacing between the propeller and the pivot point of the rudder stem 15, there should be a distance about equal to the internal diameter of the rudder wall 28. However, this spacing is controlled somewhat by the length of the fairwater, and the longer the fairwater the greater is the spacing, and vice versa for shorter fairwaters.

The recessed sides 25 and 26 of the front of the tubular rudder are cut back from the top and bottom portions 23 and 24, respectively, about one-third of the internal diameter of the rudder as defined by the wall 28. This amount of recess is variable, as will be understood in the art. However, for the instant rudder which permits of turning about 35° away from the straight-forward position, either port or starboard, this has been found to present a full access of the propeller race to the rudder so that greater maneuverability and steering control are obtained together with increased thrust in a very advantageous manner.

In Figure 8, there is shown still a further modification of this invention where a backing rudder 40 is supported forwardly of the propeller 11 on a vessel 41. This backing rudder is in addition to the previously described stern rudder 14 (which here is slightly modified by slanting lower front end 29), or where desired, the modified rudder 30, and can even be used with blade rudders. The rudder 40 is pivoted from a rudder stem 42 and may be of a design like the rudder 14, 14' or the rudder 30. The propeller shaft 12 fits entirely through the backing rudder so that the backing rudder may be turned within limits defined by its contact with the propeller shaft 12. Where desired, stop means may be provided with the rudder control so as to prevent actual engagement of the rudder with the propeller shaft.

It will be noted that in the modification of Figure 8 substantially full access and flow of water to the propeller is provided whether the propeller is used in forward or reverse, since water flows through either the rudder 40 in the forward position or through rudder 14 in the reverse position. The only change in this rudder is that the cross-sectional area of its opening is slightly increased by the area of the propeller shaft since the wheel race of necessity flows around this and cannot retract to its full extent.

Operation

For a full and complete understanding of this invention a consideration should be given to the nature of the propeller race. It has been found that the propeller race is propelled aft of the propeller in the general form of a cylindrical jet at a very high velocity with respect to the surrounding water. The propulsive force of this jet on the water from the propeller and aft of it furnishes the reaction required to propel the vessel forwardly. The force lines of this jet stream aft of the propeller are generally shown in Figure 2 where the necking-down feature to the constant diameter at point 17 has been previously discussed. Actually, this is a rotating column of water in a like manner to a screw due to the rotational effect of the propeller 11.

The increase in velocity of the water propelled through this screw as it rapidly rotates causes a decrease in pressure in accordance with the Bernoulli theorem. Simultaneously with this increase in velocity and decrease in pressure, there are serious cavitation effects and internal turbulence within the propeller race. All of these factors contribute to a very turbulent wash or roll at the water surface aft of the vessel. However, with the tubular rudder 14 or 30 of this invention as utilized, the propeller

race is enclosed and the full benefit and effect of the propulsion or thrust of the race is realized without any outside interference or disturbance. Thus, as shown in Figure 2 where the propeller race is enclosed, there is protection against outside interference from the undisturbed water medium surrounding the race which is at a higher pressure than the propeller race within the rudder. By enclosing the propeller race as shown, a full control can be had and the thrust is more efficiently utilized in a manner similar to a jet propulsion where there is very little inefficient dissipation of the high velocity race.

In Figure 3, there is shown the action of the propeller race within the rudder 14 when it is turned over to the hard port position. In this condition, the force lines on the starboard side impinge against the open flared internal side of the airfoil section 27 of the rudder and through a substantially normal or vertical impingement tend to cause the rudder to pivot in the clockwise position about the rudder stem. This action is counter-balanced by the force lines on the port side which, due to the airfoil or outwardly flaring front portion, causes a slight vacuum on the inside of the straight wall 28, as is shown in the dotted lines, to create an area of reduced pressure. This area of reduced pressure tends to cause a counter-clockwise rotation of the rudder about the rudder stem so that there are equal and opposite forces which tend to maintain the rudder in the position to which it is turned.

The particular advantage of this invention can be readily understood when compared with the operation of a standard straight-bladed rudder. In such a bladed rudder, there are a series of irregular forces upon the rudder since it is disposed vertically directly behind the propeller wheel. There are flute cycle vibrations as the propeller race is propelled aft of the propeller in the aforementioned screw-like or spiral direction, and since the rudder is right in the center there is a positive force on one side and a negative force or area of reduced pressure on the other side as each flute passes the rudder. Thus, in the case of the common blade rudder, there are two flute cycle vibrations, one at the top of the rudder and one at the bottom of the rudder as each flute passes the leading edge of the rudder. This not only causes torque on the rudder, but imparts a very substantial force or vibration to the rudder and through it to the entire ship.

Further, since the blade rudder is placed directly in the path of the wheel race, it causes a break-up or loss of the smooth, even configuration of the propeller race, and a great turbulence. Likewise, due to the relationship of the bladed rudder directly in the path of the propeller race, steering control and maneuverability are difficult to maintain in anything but the straight-forward position. Thus, when the blade rudder is turned to one position out of straight-forward, the wheel race hits the turned blade and tends to return it to the straight-forward position so that this turned position is difficult to maintain and requires a substantial amount of force or torque.

In the case of the Kort rudder and other propeller shrouded rudders, there are disadvantages since the full effect of the propeller race is lost as this race is not enclosed and controlled as has been done in this invention. Further, in addition to the loss in thrust and greater steering force required, relative to the present invention, the propeller shrouded rudders are disadvantageous because of the small clearance they have around the propeller and their increased draft. These rudders have been found to be susceptible to breakage since foreign objects, which inevitably are drawn into the propeller, tend to jam the clearance space on the outside of the propeller and are caught therein which causes breakage and disrepair of the blades of the propeller and the rudder.

Because of the comparative considerations discussed above, it has been found that the tubular rudder of this invention has greatly improved maneuverability over the blade rudder, through response to control and force or torque required, in the amount of 70%. Vibration in the employment of the rudder of this invention over the blade rudder has been extremely reduced and the forward thrust has been improved as much as 10%. Also, the wheel wash leaving the tubular rudder is smoother or flatter and causes less turbulence at the surface of the water so as to greatly reduce hazards to small boats in the neighborhood.

Experiments with the tubular rudder have also been made with respect to the Kort rudder where it has been found that steering maneuverability has been increased by about 10% and the vibration has also been very substantially reduced. Further, the thrust from the rudder of this invention has been increased by approximately 10% over the Kort rudder.

The rudder 30 of Figures 6 and 7 operate in the same manner as described above for the rudder 14 or 14'. However, in the case of the rudder 30, the operational advantages will be even greater since the capture of the propeller race is more perfectly effected, which is the prime consideration of this invention. As has been previously discussed, the propeller race actually is flattened out somewhat at the bottom due to an increase in pressure which varies directly with the depth below the surface of the water. This consideration is greater in deep draft and large vessels using propellers of substantial dimensions. In such vessels, where maximum thrust steering efficiency and maneuverability are very important, the rudder 30 has its greatest application. Such demands on large vessels as large ocean-going ships or river tow-boats of great power which are designed to push a number of barges make practical the manufacture of this specially shaped rudder, although this rudder is somewhat more difficult to fabricate than the cylindrical shaped rudder 14.

The backing rudder of Figure 8 operates in the same manner as above described for either the rudder 14 or the rudder 30 and can be made in a manner similar to either of these rudders. When a backing rudder is utilized, it surrounds the propeller shaft and, as previously mentioned, can be turned within the limits of contact with this shaft to effect steering or maneuvering of the vessel when the propeller is reversed. Since the regular rudder 14' is tubular, it provides substantially full access of flow of water to the propeller 11, which then has its propeller race projected through the tubular rudder 40 which controls in the manner above described.

Maintenance of the propeller and its shaft for vessels equipped with the rudder invention herein disclosed is especially easy and expeditious to effect. To remove the propeller shaft and propeller, the rudder 14 in either Figure 1 or Figure 8 need not be removed since the propeller can be loosened from its shaft, and the shaft, after the removal of the propeller, can then be withdrawn through the bearing 13 out through the rear end 21 of the rudder. The rudder need not be touched at all in

the propeller and shaft removal operation, which is of great advantage over the common blade rudder.

It is obvious that various changes and modifications may be made in this invention as will be apparent to those skilled in the art. Such changes are within the scope of this invention as defined by the claims appended hereto.

What is claimed is:

1. A rudder for marine vessels adapted to be used in spaced relation behind a propeller on the vessel, said rudder comprising a hollow shell completely open and unobstructed at its front and rear ends, said shell having a continuous wall at its top, bottom and sides to define a hollow space enclosed by said shell, said hollow space being slightly smaller than the diameter of the propeller with which the rudder is adapted to be used, said top, bottom and side walls defining a substantially cylindrical shell, and pivot means whereby the rudder can be pivoted, said shell having its side walls at the front end recessed rearwardly of the front top and bottom walls.
2. A rudder for marine vessels adapted to be used in spaced relation behind a propeller on the vessel, said rudder comprising a hollow shell completely open unobstructed at its front and rear ends, said shell having a continuous wall at its top, bottom and sides to define a hollow space enclosed by said shell, said hollow space being slightly smaller than the diameter of the propeller with which the rudder is adapted to be used, said top, bottom and side walls defining a shell having a front opening of rounded cross section, said cross section being substantially circular at the top and sides and somewhat flattened at the bottom.
3. In combination with a vessel having a bladed propeller, a hollow backing rudder for steering the vessel when the propeller is reversed, said rudder being spaced forward of the propeller and being open at its opposed ends to receive and exhaust the propeller race when the propeller is operated in reverse, and to pass water therethrough with a minimum of flow restriction when the propeller is operated in forward.
4. In combination with a vessel having a bladed propeller, the improvement comprising a hollow rudder, said rudder being spaced aft of the propeller, said rudder having an open front end to receive said propeller race and an open rear end to exhaust the race, a hollow backing rudder for steering the vessel when the propeller is reversed, said rudder being spaced forward of the propeller and being open at its opposed ends to receive and exhaust the propeller race when the propeller is operated in reverse, and to pass water therethrough with a minimum of flow restriction when the propeller is operated in forward.
